[57] CLAIM

The ornamental design for a game target, as shown and described.

DESCRIPTION

FIG. 1 is a front elevational view of the game target showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is a left side elevational view thereof; with support shown in a position of game target in use; shown for clarity of illustration.

The broken line showing of numbers and description is for illustrative purpose only and forms no part of the claim.
